SLIP RING CUTTING MACHINE

Leo T. Schuler, Ruthven, Iowa

Application June 30, 1945, Serial No. 602,623

5 Claims. (Cl. 82—4)

(Granted under the act of March 3, 1883, as
amended April 30, 1928; 370 O. G. 757)

1

The invention described herein may be manufactured and used by or for the Government for governmental purposes, without payment to me of any royalty thereon.

This invention relates to a portable turning tool and is particularly adapted to the truing up and refinishing of the slip rings which are mounted on the rear of the hub of an electrically controlled variable pitch aircraft propeller of which the Curtiss electric propeller is an example. 10

An engine lathe of large enough capacity to swing the larger size propellers without disassembly of the blades from the hubs would be prohibitive both as to size and cost, and therefore, prior to this invention, it has been the custom when the slip rings became scarred or pitted to such an extent as would seriously affect the brush contact, to remove the propeller from the aircraft, disassemble the blades from the hub, swing the hub in a lathe of suitable capacity, and refinish the outer surface of the rings by turning. But even where the blades are disassembled from the hub, a lathe of considerable size and weight is required.

Such a lathe cannot readily be made a part of a mobile repair unit, but, because of the large size and weight, is furnished only to general depots. It had therefore become the custom when the slip rings of a propeller were worn or damaged, to remove the propeller from the shaft and ship it to a general depot for refinishing, where the blades are disassembled from the hub, the slip rings turned, the hub and blades reassembled, and the repaired propeller shipped back to the repair unit from which it was sent, with the consequent loss of the time that the propeller was in transit.

It therefore became an object of this invention to provide a portable turning tool, light enough to be easily handled by a single repairman, but equally as effective in performing the intended function as an engine lathe weighing several tons, to the end that each and every mobile repair unit may be possessed of one of the improved turning tools at a relatively small total cost.

Another object is to provide simple and inexpensive means whereby the several sizes of propellers in current use may be operated upon with a single turning tool.

I attain these and other objects and advantages in the mechanism hereinafter described and shown in the drawing, wherein:

Fig. 1 is an end elevation of the assembled tool, 55

a portion being broken away to show the interior construction.

Fig. 2 is an axial section taken at 2—2 of Fig. 1.

Like reference characters refer to like parts throughout the several views.

Referring now to the drawing, an arbor 10 is of such external dimensions as will fit snugly into the propeller hub after it has been removed from the shaft, the rear cone 12 and the threads 14 being of the same dimensions as are found on the propeller shaft, whereby the propeller shaft retaining nut may be used to secure the arbor 10 firmly in the propeller hub. The arbor may be bored out as at 16 to lighten it. Different sized arbors may be provided for hubs of different sizes, or sleeves of appropriate contour may be provided for bushing up a smaller arbor for use in a larger hub.

The rear end of the arbor 10 carries a tool guide in the form of an extension 18, the axis of which must be coincident with the axis of the arbor since the concentricity of the reworked rings will depend on the concentricity of the extension 18 with the arbor 10. The extreme rear end of the extension 18 is further reduced in diameter at 20, and provided with a flanged bushing 22 which may preferably be pressed on or at least closely fitted to the reduced part 20, whereby its external surface may serve as a journal bearing for a planetary gear carrier 24.

The carrier 24 is centrally bored for a running fit on the outside of the journal bushing 22, a washer 26 being held to the end of the reduced part 20 by screws 28, which precludes the bracket 24 from moving axially on the bushing 22 upon which it rotates. Two additional openings are provided near the outer ends of the arms of the bracket for the bearing bushings 30. The axes of these two additional openings should be exactly parallel with the hub axis and may preferably be equidistant therefrom. The bearing bushings 30 may preferably be press fitted to their respective openings.

Freely rotatable in each bearing bushing 30 is a flanged feed sleeve 32, an integral externally threaded portion 34 extending rearward from each feed sleeve to receive an internally threaded gear 36 and a lock nut 38, whereby the sleeve 32, gear 36 and lock nut 38 rotate as a unit.

The assembly of the parts designated by numerals 32, 34, 36 and 38 may be referred to as the planetary gear and hub assembly. It should be understood, however, that a journal which will rotate in the carrier 24 may be made integral with the gear, and internally threaded

for the feed screw 54, if provision is then made to prevent axial movement of the journal with respect to the carrier, in which case the assembly may be referred to as the planetary gear and journal unit.

A small pinion 40 has a shank 42 which is pinned at 44 to prevent both rotation and axial movement in the reduced part 20. Pinion 40 is in toothed engagement with both gears 36. A cutter arm 46 is bored tapered to contain an externally tapered split bushing 48 which is drawn into the tapered bore by a nut 50; the nut 50 being provided with a handle 52. By carefully maintaining the bushing 48 in close adjustment, the arm 46 may have the necessary rotative and axial movement on the tool guide 18 without having noticeable play. Obviously, the bushing 48 may be omitted and the cutter arm 46 fitted directly to the tool guide 18 in cases where less precision is demanded.

Externally threaded feed screws 54, with axes coincident with the axes of the feed sleeves 34, have an unthreaded portion 56 anchored in the cutter arm 46 and pinned therein as at 58 to preclude both radial and axial movement therein. The external threads of the feed screws 54 are fitted to corresponding internal threads in the feed sleeves 34. A cover 60 is secured to the ends of the feed sleeves 54 by screws 62. Cover 60 is provided to keep chips or other foreign matter from the gearing.

The outer ends of the cutter arm 46 are bored for the cutter bar 64 and the hand crank 66, which are of exactly equal diameters. The axes of the cutter bar 64 and the hand crank 66 are both parallel to the axis of the arbor 10, but the axis of the hand cranks 66 is spaced apart farther from the arbor axis than the axis of the cutter bar. Slip rings of larger diameter may therefore be turned by placing the cutter bar in the hand crank opening and vice versa.

Set screws 68 and 70 hold the cutter bar 64 and hand crank 66 in position. The cutter bar 64 is provided with a groove 72 for the pointed set screw 68. The cutting bit 74 is preferably of square steel, the bit being slidably in a corresponding square opening extending transversely through the end of the cutting bar. An adjusting screw 76 which regulates the depth of the cut to be taken, and a locking screw 78 holds the bit in the adjusted position.

The assembly of the cutter arm 46 and its associated parts corresponds to the carriage of a lathe in that it follows a guideway along the axis of relative rotation between the tool and the work, and may therefore hereinafter be so designated.

The operation of the device is as follows:

The propeller is first removed from the propeller shaft and placed in any convenient position with the back of the propeller toward the repairman. The arbor 10 is inserted in the propeller hub and secured with the propeller shaft retaining nut (not shown). The screw 68 may now be loosened and the cutter bar 64 adjusted axially until the bit 74 is adjacent one of the rings. The screw 68 is then tightened. The bit 74 may next be adjusted to the desired depth of cut by means of the adjusting screw 76 and locked with the screw 78. As the cutter arm 46 is rotated about the extension 18 by means of the crank 66, the gears 36 will roll around the pinion 40, the gears thereby being rotated on their own axes about one turn to seven turns of the crank. By providing the feed screws 54 with forty

threads per inch, each turn of the crank advances the bit axially $1/7 \times 1/40 = 1/280$ or about .036 in. When a rough cut has been taken in this manner, the locking screw 78 may be loosened, the bit 74 removed and turned one-half turn and replaced, the screw 76 adjusted for a finished cut and locked with the screw 78. The crank 66 is now turned backward which feeds the cutter arm 46 in the direction opposite of that taken for the rough cut.

Having described an embodiment of my invention, I claim:

1. A portable turning tool for refinishing the slip rings on the rear end of an electric variable pitch aircraft propeller hub which comprises, an arbor adapted to fit the bore of the propeller hub, a cylindrical tool guide integral with the arbor, coaxial therewith, and extending rearwardly therefrom, the rear end of said tool guide being stepped down to a smaller diameter, a flanged journal bushing carried on the said smaller diameter, a sun gear fixed to the rear end of said smaller diameter, a planetary gear carrier rotatable on said journal bushing, axially parallel and axially equidistant internally threaded feed sleeves having rotative bearing in said carrier, planetary gears fixed to said feed sleeve for coincident rotation therewith and in constant mesh with said pinion, an adjustable bearing bushing on said tool guide having free rotative and axial movement thereon, a cutter arm carried on the outside of said bearing bushing, feed screws having one end anchored in said cutter arm and the other end threaded and fitted to the internal threads in said feed sleeves, a cutter bar adjustable axially in an axially aligned opening near one end of said cutter arm, an adjustable tool bit in one end of said cutter bar, and a hand crank secured in an axially aligned opening near the other end of said cutter arm.

2. A portable turning tool for refinishing the slip rings on the rear end of an electric variable pitch aircraft propeller hub which comprises, an arbor adapted to fit the bore of the propeller hub, a cylindrical tool guide carried on the arbor, coaxial therewith, and extending rearwardly therefrom, a journal bushing carried on the rear end of said cylindrical tool guide, a sun gear fixed to the rear end of said cylindrical tool guide, a planetary gear carrier rotatable on said journal bushing, axially parallel and axially equidistant internally threaded feed sleeves having rotative bearing in said carrier, planetary gears fixed to said feed sleeve for coincident rotation therewith and in constant mesh with said pinion, a bearing bushing on said tool guide having free rotative and axial movement thereon, a cutter arm carried on the outside of said bearing bushing, feed screws having one end anchored in said cutter arm and the other end threaded and fitted to the internal threads in said feed sleeves, a cutter bar adjustable axially in an axially aligned opening near one end of said cutter arm, an adjustable tool bit in one end of said cutter bar, and a hand crank secured in an axially aligned opening near the other end of said cutter arm.

3. A portable turning tool for refinishing the slip rings on an electric propeller hub which comprises, an arbor adapted to fit the bore of the propeller hub, a tool guide carried by the arbor and extending axially therefrom, a journal carried by the said tool guide, a sun gear fixed to the rear end of said tool guide, a planetary gear carrier rotatable on said journal, axially parallel and axially equidistant internally threaded plan-

etary gear and hub assemblies, said hubs having rotative bearing in openings in said carrier and said gears being in toothed engagement with said pinion, a cutter arm slidable axially on said tool guide, feed screws having one end anchored in said cutter arm and the other end threaded and fitted to the internal threads in said planetary gear and hub assemblies, a cutter bar adjustable axially in an axially aligned opening near one end of said cutter arm, an adjustable tool bit in one end of said cutter bar, and a hand crank secured in an axially aligned opening near the other end of said cutter arm.

4. The device defined in claim 3 wherein the openings near the ends of the cutter arm, which are provided for the cutter bar and the hand crank, are of equal size but at different distances from the axis of the arbor.

5. A portable turning tool for refinishing the slip rings on a propeller hub which comprises, an arbor adapted to fit the bore of the propeller hub, a tool guide carried by the arbor and axially aligned therewith, a journal, coaxially supported by said arbor, a sun gear coaxially supported by

said arbor, a planetary gear carrier rotatable on said journal, axially parallel and axially equidistant internally threaded planetary gear and journal units, said journals having rotative bearing in openings in said carrier and said gears being in toothed engagement with said sun gear, a cutter arm movable axially on said tool guide, feed screws having one end anchored in said cutter arm and the other end threaded and fitted to the internal threads in said planetary gear and journal units, radially adjustable cutting means supported by said cutter arm, and means to rotate said cutter arm.
